UNITED STATES PATENT OFFICE

JOHN ROYDEN PEIRCE, OF NEW YORK, N. Y., ASSIGNOR, BY MESNE ASSIGNMENTS, TO THE TABULATING MACHINE COMPANY, OF NEW YORK, N. Y., A CORPORATION OF NEW JERSEY

TABULATING MACHINE

Application filed January 12, 1926. Serial No. 80,854.

This invention pertains to record-controlled tabulating machines and has for its particular object the provision of improved devices by which combinational hole records such as the Peirce (in which there may be more than one hole per column) may be analyzed and the readings converted into single hole readings suitable for controlling accumulators of the Hollerith type which are designed for use in connection with record cards having only one hole per column.

For purposes of illustration and simplicity of description the invention is explained in connection with the Peirce number code instead of the Peirce alphabetical code because the number code has only four index positions while the alphabetical code has six positions, but the invention may be used in connection with the Peirce alphabetical code or any known code having a plurality of holes in a single column.

In the drawings,

Fig. 1 is an end view of the invention in which a Hollerith accumulator is shown in dotted outline.

Fig. 2 is the Peirce code for numbers.

Fig. 3 is a plan view of Fig. 1 showing a portion of a Hollerith accumulator, the gearing connecting the accumulator with the present invention and two units of the invention.

Fig. 4 is a detail view of the combs.

Fig. 5 is a circuit diagram of the device.

Fig. 6 shows a part of the mechanism in Fig. 1, but in a different position.

A Hollerith tabulator is shown at 10 (Figs. 1 and 3), and connected therewith by gears 12 and 14 is the mechanism of my invention which is supported by a frame-work 16. Gear 14 is fast on shaft 18 which therefore turns in synchronism with the accumulator mechanism. Fast on shaft 18 is a series of spoked discs 20, one disc for each column to be analyzed on the card. Fast on the rim of each disc 20 are brackets 22 circumferentially grooved to accommodate four ring shaped combs 24, one for each of the code index positions A, B, C and D. The combs are free to move circumferentially in their grooves to a limited extent relatively to their support-

ing disc 20. Pivots mounted on pins 26 near the rim of each disc 20 are four pawls 28, each having an extension 30 best shown in Fig. 4, each extension having a latch portion 32 so positioned as to cooperate with a notch 34 on the inner edge of one of the combs 24. Each pawl 28 has a tail 36 designed to cooperate with a pin 38 carried by arm 40 of armature 42 of magnet 44, the armature being pivoted in the frame at points 43.

Normal position of the parts is shown in Fig. 1, in which each pawl 28 is latched in its notch 34 in its corresponding comb 24, so that if disc 20 rotates clockwise all combs 24 carried by that disc will rotate with it. Each comb 24 is urged in counterclockwise direction by a spring 46 connecting each ring 24 with a bracket 22.

If any pawl 28 is moved so as to unlatch its particular comb 24 spring 46 will draw that comb counterclockwise relatively to its disc 20 until the inwardly projecting arm 48 of comb 24 contacts with bail rod 50, as shown in Fig. 6. Disc 20 and comb 24 continue to rotate in the direction of the arrow but the comb 24 has been slightly displaced rearwardly with relation to its supporting disc 20.

Bail 50 extends through all the units of the device and is supported at its ends by vertical arms 52, pivoted on the two end discs 20 at 54. One of the arms 52 is provided with a horizontal arm 56 bearing at its free end a roller 58 running in groove 60 of box cam 62 which is fast to the frame of the machine. This cam groove has a concentric portion and a substantially straight chordal portion. Bail 50 and its connecting parts just described are all carried by discs 20 as the discs rotate. While roller 58 is in the concentric portion of the cam groove, rod 50 does not move relatively to discs 20, but while roller 58 passes through the straight portion of the cam groove, arm 56 is actuated about pivot point 54 to move rod 50 first clockwise relatively to discs 20 and then back to normal position. When rod 50 moves clockwise, or forwardly, it engages all arms 48 and moves all combs 24 forwardly relatively to discs 20 until all

combs 24 are again latched in normal positions by their latches 32 attached to pawls 28. In other words, rod 50 is a restoring bail actuated by cam 62 to bring discs 20 and 5 combs 24 into their normal relationship.

Bearing on the outer rims of each set of four combs 24 is a latch bar 64 carried by pawl arm 66 pivoted on pin 68 and pressed against the combs by spring 70. Pivot pin 68 10 is carried on one end of horizontal lever 72, pivoted on the frame at 74. The outer end of lever 72 when in normal position (Fig. 1) latches spring blade 76 to the right so as to hold open contact 78.

15 With the above construction features in mind the operation of the device may be readily understood.

Peirce cards are fed one by one, in the usual manner, from stack 80 by picker 82 20 between feed rolls 84, as indicated diagrammatically in Fig. 5. While passing through the feed rolls the card passes between contact brushes 86 and their corresponding contact blocks 88. Each brush traverses a column on the card. For purposes of illustration only three brushes are shown but as many may be used as there are card 25 columns. Each card has a reading zone in which all perforations are placed. In that 30 zone any column may have holes in an any one or two of the positions A, B, C, and D, as in Fig. 2, which shows the Peirce code for numbers. If, in any column, there is a single hole in A position it means 1; a 35 single hole at B position means 2; two holes, one at A and one at C means 3; and so on.

Cards are fed past the brushes at regular 40 intervals and the rotation of the discs 20 is synchronized with the card travel so that 45 the four latch pawls 28 pass magnet arm 40 as the four card index positions pass the brushes. Each pawl 28 with its latch 32 cooperates with one of the four combs 24, as previously explained, and both pawl 50 and comb are coordinated with a particular index position, so in order to clarify the description of operation, the combs 24, pawls 28, and latches 32 have been marked (Figs. 4 and 6) with the code position letters A, B, C, and D shown in Fig. 2.

Cards are fed past the brushes bottom 55 first, therefore the index positions on the card pass the brushes in the order A, B, C, and D. If any brush finds a hole in the card at (say) the A position, contact is made through that hole between brush 86 and block 88, the magnet 44 coordinated to that column is energized, and its armature 42 actuated. This swings arm 40 and moves 60 pin 38 into the path of the tail 36 of the "A" pawl 28 which at that instant is approaching pin 38. When the pawl contacts with pin 38 latch 32 is withdrawn from its notch 34 and the corresponding "A" comb 35 24, being unlatched, is drawn rearwardly by

its spring 46, as above explained. Magnet 44 is deenergized before the B index position of the card is under the brush, and armature 42 with its arm 40 and trip pin 38 have been restored to normal position by spring 90 acting with the first of the restoring cams 92 which are so placed on the side of disc 20 as to contact with the end of arm 40 after each pawl 28 has been actuated and before the next pawl is in position to be actuated.

70 There is one disc 20 corresponding to each card column, and each disc 20 carries four combs 24, one for each index position A, B, C, and D. All the discs 20 rotate in unison and by the time the pawls 28 have passed the trip pins 38, all combs 24 corresponding to perforations in the card columns have been moved a step rearwardly with relation to their respective discs, as described above for an A comb. If one perforation is found in a column, one comb is displaced; if two perforations are found in a column, the two combs corresponding to those perforations are displaced.

75 We are now ready to consider what happens after the proper combs 24 are displaced relatively to their discs 20. By referring to Fig. 4 it will be seen that each comb 24 is provided in its outer rim with a series of notches 94. Fig. 4 shows the combs in normal position and it will be noted that nowhere is there a set of notches aligned with each other on all four combs. For instance, at the 5 position the notches of combs A, B, and D are aligned, but there is no corresponding notch in the C comb. It will also be noted that if the C comb be drawn a step rearwardly that it will present a notch in alignment with the notches in the other three combs. It will be further noted from Fig. 2 80 that the digit 5 is represented in the Peirce code by a single perforation at C position. In other words, the comb which, in normal position, fails to present a notch 94 in alignment with the notches in the other combs is the comb corresponding to the index position which designates that digit in the code. If the code requires two perforations to 85 designate a digit, then the two combs 24 corresponding to those perforations must be displaced rearwardly to provide a set of four aligned notches. For instance, the digit 6 is 90 designated by perforations at A and D positions, and it will be seen (Fig. 4) that it is the A and D combs that must be displaced to align four notches at the six position, and so on for all other digits. The obstructing combs at any digit position are those corresponding to the index perforations designating that particular digit, and when the 95 obstructing comb or combs have been displaced a step rearwardly, all four notches 94 are aligned at that digit position on the combs. When one set of four notches is aligned, no other set can be aligned.

The digit positions are so located on the combs 24 that, as the combs rotate in the direction indicated by the arrows, the digit positions pass any given point such as latch bar 64, in the same order, and at the same speed, as the index perforations of a Hollerith card pass the brushes.

As already described, latch bar 64 is constantly pressed against the outer rims of combs 24 by spring 70. Whenever a set of aligned notches comes opposite bar 64 it drops into the notches, assuming the position shown dotted in Fig. 6 in which position it is carried along by the rotating combs until the tail 96 of pawl 66 contacts with beveled stop 98 which forces bar 64 out of notches 94. When pawl 66 was moved to the dotted position, its supporting lever 72 was forced to the position shown dotted in Fig. 6, thereby unlatching contact spring 76 and allowing contact 78 to close, thereby sending an impulse through contact 100 and magnet 102 of the Hollerith counter and actuating it in the regular manner to turn its registers 104 an appropriate amount.

Summarizing, as the Peirce card passes brushes 86, magnets 44 are energized and armatures 42 actuated to control pawls 28 which in turn control combs 24 to arrange a set up of notches, which, through the instrumentality of pawls 66 are enabled to actuate the Hollerith counter exactly as it is actuated by Hollerith cards.

After the cycle of operations is completed a pin 106 on an end disc 20 contacts with a restoring lever 108 (Figs. 1 and 3) and the restoring bail 110 pushes all contact blades 76 to the right sufficiently so that they may be latched in normal position (Fig. 1) by lever 72; levers 108 and 72 are retained in their normal positions by coil springs 112 and 114 respectively. Rings 24 are restored as already described by bail 50.

The electric circuits and their control will be understood from Fig. 5. Power for the machine is furnished by motor TM which receives current from the line through switch 116, and drives the machine by belt 118 and various gears shown diagrammatically.

Current for the analyzing brushes flows from the outside source through switch 120, line 122, contact 124, common brush holder 126, brush 86, block 88, line 128, magnet 44, and line 130 to opposite side of line.

When a contact 78 is closed by the operation of combs 24 on pawl 66, current flows from left side of line through line 132, line 134, contact 78, line 136, Hollerith counter contact 100, and through counter magnet 102 to right side of line.

Contact 124 is controlled by four-point star wheel 138 to allow contact at each index position but prevent sparking at the card, as is customary in devices of like nature.

I claim

1. In a machine of the class described, in combination, means to feed record cards having combinational holes in columns, a device to sense the combinational holes in the records, a rotating disc, a plurality of ring shaped combs mounted on said disc, means controlled by said sensing device for setting said combs relatively to said disc, and mechanism operable by said combs after being set by said setting device. 70 75

2. A record controlled machine comprising record analyzing means consisting of a single analyzing element for each record column, a plurality of settable elements, a single operating member for selectively setting any of said elements and a single operating device for said member controlled by the record analyzing means to operate said single operating member to effect set ups of said settable elements according to character designations on controlling records. 80 85

3. A record controlled machine comprising record analyzing means consisting of a single analyzing element for each record column, a plurality of settable elements, a common member for selectively setting said elements and means for relatively moving said elements and said member to successively bring each element into cooperation with said member and means controlled by the analyzing means for selectively operating the member in its several relative positions to effect set ups of said settable elements according to character designations on controlling records. 90 95

4. A record controlled machine comprising record analyzing means consisting of a single analyzing element for each record column for successively searching index point positions on controlling records, a plurality of settable elements, a common member for selectively setting said elements and means for relatively moving said elements and member to successively bring them into different cooperating positions as a controlling record is in the process of analysis and means controlled by said analyzing means for selectively operating the member in its several relative positions to effect set ups of said settable elements according to character designating index 100 105 110 115 points on controlling records.

5. A record controlled machine comprising record analyzing means consisting of a single analyzing element for each record column for searching index point positions on controlling records while the latter are in motion, a plurality of settable elements, a common member for selectively setting said elements and means for relatively moving said elements and member to successively bring them into different cooperating positions concurrently with the movement of a controlling record past the analyzing means, and means controlled by the analyzing means for selectively operating said member in its sev- 120 125 130

- eral relative positions to effect set ups of said settable elements according to character designating index points on controlling records.
6. A record controlled machine comprising record analyzing means for searching a plurality of index point positions on controlling records, a plurality of settable elements equal in number to the index point positions on records, a common member for selectively setting said elements and means for relatively moving said elements and said member to bring the latter successively into cooperation with each element and means controlled by the analyzing means for selectively operating said member in its several relative positions to effect set ups of said settable elements corresponding to character designating index points on controlling records. 70
- 10 7. In a machine of the class described, a translator controlled by record cards and including a plurality of settable elements, a single card reading device for successively searching index point positions on controlling cards which positions in number correspond to the number of the aforesaid elements and a common setting member for all of said elements with means for presenting the same to each element in succession and means controlled by the reading device to selectively operate said member according to index points on the record cards. 75
- 15 8. A record controlled machine including analyzing means for searching index point positions on a controlling record while the record is in motion, a plurality of settable elements, a single operating member for selectively setting any of said elements and a single operating device for said member controlled by the analyzing means to operate said single member to effect set ups of said settable elements singly or in combinations according to index combinational points on controlling records. 80
- 20 9. A record controlled machine including analyzing means for successively searching index point positions on individual character designating fields of a controlling record, a plurality of settable elements for each field, a single operating member for selectively setting said elements singly or in combinations and a single operating device for said member controlled by the analyzing means to operate said single member to effect set ups of said settable elements according to combinational index points on the corresponding character designating field of a controlling record. 85
- 25 10. A record controlled machine comprising record analyzing means adapted to analyze combinational index point designations, a rotatable element having a plurality of settable devices mounted thereon and a common member controlled by said analyzing means for setting said devices according to combinational index point designations on controlling records and means controlled by said devices as set for manifesting the data represented by the combinational settings. 90
- 30 11. A record controlled machine comprising record analyzing means for successively searching index point positions on a controlling record, a rotatable element having a plurality of settable devices mounted thereon along a circumferential line, a common element mounted in proximity to said rotatable element for setting said devices, means for rotating said rotatable element to present a different settable device to said common member for each index point position on a record and means controlled by said analyzing means for operating said common member and means for translating the settings of said elements into timed electrical impulses. 95
- 35 12. A translating device for converting pulses corresponding to a combinational index point code of character designation into pulses corresponding to a single index point code of character designation comprising a plurality of settable elements mounted on a rotatable member, a single operating member for setting said elements with electromagnetic means for controlling the same, a switch and means coacting with said settable elements for operating the switch at differential times corresponding to different set ups of said settable elements. 100
- 40 13. A translating device for converting pulses corresponding to a combinational index point code of character designation into pulses corresponding to a single index point code of character designation, comprising a plurality of settable elements mounted on a rotatable member and corresponding in number to the index points of the combinational code, means for setting said elements in combinations, a switch and means for operating the same in different angular positions of the rotatable member for different combinational set ups of the settable elements. 105
- 45 14. A translating device for converting pulses corresponding to a combinational code of character designation into pulses corresponding to a single index point code, comprising a plurality of settable elements mounted on a rotatable member and corresponding in number to the index points of the combinational code, means for setting said elements in combinations according to the combinational code, a switch and means cooperating with the settable elements for operating the switch at differential times to initiate timed pulses representing by their timing the characters corresponding to the set ups of the elements. 110
- 50 15. A translator for translating combinational index point designations into single index point designations including a plurality of settable elements corresponding in number to the index points of the combinational code. 115
- 55 60 65 70 75 80 85 90 95 100 105 110 115 120 125 130

ber to the index point positions of a combinational code, a common member for setting up said elements, means for operatively presenting each of said elements to said member in succession for selective operation thereby, an electromagnet for selectively operating said member, and means for converting combinational settings of said elements into corresponding character manifestations according to a single index point code.

16. In a machine of the class described, analyzing mechanism for successively searching combination code index points on records, translating mechanism for translating the combinational index point designations into single index point designations including a plurality of settable elements corresponding in number to the index point positions of the combinational code, a common member for selectively setting up the elements, an electromagnet controlled by the analyzing mechanism in each successive searching operation to selectively operate said common member means for operatively presenting said elements to said member successively in synchronism with analysis of combinational index point designations by the analyzing mechanism and means for converting the combinational settings of said elements into corresponding character manifestations according to a single index point code.

17. A translator comprising a rotatable member, a plurality of combs mounted thereon, means for displacing said combs relatively to each other in combinations and means for converting the different settings of said combs into differently timed impulses.

18. A translator comprising a rotatable member, a plurality of combs mounted thereon, means for independently displacing each of said combs relatively to the others, a device for initiating differentially time impulses and means for operating said device in a different angular position of said rotatable member for different shifted combinations of said combs.

19. A translator comprising a rotatable member, a plurality of combs mounted thereon, each provided with a series of radial notches, means for shifting said combs relatively to each other in combinations to bring notches in all of them in alignment along a definite radial line for each shifted combination, a feeler member fixed in position to search the aligned notches and a switch operated by said feeler member to initiate differentially timed current impulses for aligned notches in the combs along different radial lines of the rotatable member.

20. A record controlled machine including means for analyzing combinational index points on controlling records, a plurality of rotatable combs and means controlled by the analyzing means for shifting the combs in combinations according to combinational in-

dex point designations on the records, means for rotating the combs after shifting and means controlled conjointly by the combs for initiating single differentially time impulses for each different combinational shifting.

21. A record controlled machine comprising record analyzing means, a plurality of settable elements, a single operating member for selectively setting said elements in combinations which may include more than one element and a single operating device for said member controlled by the record analyzing means to operate said single operating member to effect combinational set ups of said elements according to combinational character designations on controlling records.

22. A record controlled machine comprising record analyzing means, a plurality of settable elements, a common member for selectively setting said elements in combinations which may include more than one element, means for relatively moving said elements and said member to successively bring each element into cooperation with said member and means controlled by the record analyzing means for selectively operating the member in its several relative positions to effect combinational set ups of said settable elements according to combinational character designations on controlling records.

23. A record controlled machine comprising record analyzing means, a plurality of settable elements, a common member movable for selectively setting said elements in combinations which may include more than one element and means controlled by the record analyzing means for moving said movable member to effect combinational set ups of said elements according to combinational character designations on controlling records.

24. A record controlled machine comprising record analyzing means, a plurality of settable elements, a common member movable for selectively setting said elements in combinations which may include more than one element, means for moving said elements relatively to said movable member to bring each element successively into the path of movement of said movable element and means controlled by the analyzing means for selectively effecting movement of said common movable member to effect combinational set ups of said settable elements according to combinational character designations on controlling records.

25. A record controlled machine comprising record analyzing means, a plurality of settable elements, a single operating member for selectively setting said elements, single operating device for said member controlled by the record analyzing means to operate said single operating member to effect set ups of said settable elements and means to translate the set ups into timed electrical impulses.

26. A record controlled machine including

record analyzing means consisting of a single analyzing element for each record column, a plurality of settable elements, a common member for selectively setting said elements and electromagnetic means controlled by the record analyzing means to operate said common member to effect set ups according to character designations on controlling records.

10 27. A translator comprising a plurality of settable elements, a common member for selectively setting said elements in combinations which may include more than one element and an electromagnet for selectively 15 operating said common member to effect different set ups of the settable members.

In testimony whereof I hereto affix my signature.

JOHN ROYDEN PEIRCE.
